UNITED STATES PATENT OFFICE.

LOUIS E. ENDSLEY, OF PITTSBURGH, PENNSYLVANIA, ASSIGNOR TO FORT PITT MINE EQUIPMENT COMPANY, A CORPORATION OF PENNSYLVANIA.

CAR-TRANSFER APPARATUS.

Application filed August 31, 1926. Serial No. 132,696.

My invention relates to car transfer apparatus, and particularly to a chain rail conveyer, wherein chain links are provided with rail sections upon which the wheels of a car 5 may be supported and transferred from one position to another.

My invention has for one of its objects, the provision of a form of apparatus, whereby cars may be moved from a pair of fixed 10 track rails to the rail sections of the chain links, without interfering with the movement of said links and without danger of derailment of the car.

Another object of my invention is to simplify and improve generally the structure and operation of car transfer apparatus.

Briefly stated, my invention comprises the provision of rail approach structure that may support either the flanges of the wheels 20 alone, or support both the flanges and treads of the wheels when the car is entering upon the conveyer. This rail approach may be in the form of an extension of the fixed track rails or be made separately therefrom and 25 interposed between said rails and said conveyer.

One form which my invention may take is shown in the accompanying drawing wherein Figure 1 is a plan view of transfer 30 apparatus embodying my invention; Fig. 2 is a side elevational view thereof; Fig. 3 is a plan view, on an enlarged scale, of a portion of the apparatus of Fig. 1; Fig. 4 is a side elevational view of the apparatus of 35 Fig. 3, and Figs. 5, 6 and 7 are views taken on the lines V—V, VI—VI and VII—VII, respectively, of Fig. 3, and on a still further enlarged scale.

For the purpose of illustration, I have 40 shown my invention in connection with a chain rail haul for mine cars 10, that are provided with the usual flanged wheels and are moved to and from the conveyer over the usual stationary track rails 11 and 12. The rails 11 are shown as lying in a plane 45 lower than that of the rails 12. Track approaches or point rails 13 are provided intermediate the rails 11 and the conveyer, and are of such form, as hereinafter described in

detail, that the cars can be readily transferred from the rails to the conveyer. Point rails 14 are provided for supporting the car wheels when they pass from the conveyer to the fixed rails 12.

The conveyer is composed of a suitable framework 15 in which a driving shaft 16 and a driven shaft 17 are journaled, the shaft 16 being driven from any suitable source of power (not shown). A pair of sprocket wheel devices 18 is mounted upon each of the shafts 16 and 17, such sprocket wheels being shown more clearly in Figs. 3 and 4 and being provided with axially spaced disc-like members having recesses 19 that serve as pockets for rollers 20 which are carried on shafts 21 that are pivotally connected to links 22 whose upper portions, as shown in 22a in Fig. 5 are in the form of rail heads.

When the rollers enter the upper chain flights they pass between the flanges of channel irons 23 and 24, which serve to guide the supporting rollers 20 and their links 22 in proper vertical and lateral position so that a vertically rigid support is provided for the car wheels, and so that spreading of the 70 chains and consequent derailment of the cars is avoided. The lower chain flights are guided by channel irons 25 which prevent sagging and swaying of the lower idling 75 chain flights. The rail heads of the links 22 are of such form that a substantially continuous track for the car wheels is formed by those links which lie in the upper chain flights at any given period. Stops or horns 80 26 are pivotally or otherwise secured to certain of the chain links so that as the sprocket wheels 18 are driven in a counter-clockwise direction, a car moving from the lower track rails 11 and the conveyer will be held by the horns 26 against backward movement 85 until it has been deposited upon the rails 14 and 12. On the other hand, if a car is to be transported from the higher rails 12 to the lower rails 11, the direction of movement of the conveyer is reversed, and the horns 26 prevent movement of the car independently 90 of the conveyer.

The point rail members 13 and 14 are of

similar construction so that a description of the members 14 will suffice for both. The members 14 have web portions 28 that are riveted or bolted to the framework 15 and 5 are each provided with a head portion 29 that serves as a continuation of the adjacent fixed track rail 12. The rail members 14 are cut away forwardly of their head portions 29 as indicated at 30 in Fig. 3 so that 10 the rail head portions 22^a of the links 22 can pass around the sprocket wheels 18 and their upper surfaces be brought into approximate alignment with the tops of the rail members 12 and 29.

15 The cutting away of the rail members 29 at 30 leaves insufficient material to properly support the treads of the wheels of heavy cars or locomotives, and I therefore form each of the rail members 14 with a 20 grooved or channeled portion 31 that serves to support the wheels by engagement with their flanges. The grooved portion 31 of each rail member 14 is inclined slightly, at its forward end, as shown in Fig. 4, so that 25 the wheels will be transferred smoothly to the chain rails 22. The forward ends of the rail approaches 13 and 31 are rigidly supported upon cross beams 15^a of the framework 15 of the apparatus and extend 30 such distance past the adjacent sprocket wheel 18, that the weight of a car wheel will not be deposited upon a chain link 22 until the rollers at both ends of said link have entered upon the bottom flanges of 35 the channels 23 and 24.

I claim as my invention:

1. The combination with a chain rail conveyer for flanged wheels, of a track approach having a rail head portion spaced from and in approximately longitudinal alignment with the chain rail and having a portion for supporting a wheel flange when the wheel is passing across the space between the chain rail and said rail head portion.
- 10 2. The combination with a chain rail conveyer for flanged wheels, of a track approach having a rail head portion spaced from and in approximately longitudinal alignment with the chain rail and having a portion for supporting a wheel flange when the wheel is passing across the space between the chain rail and said rail head portion, the said flange supporting portion extending alongside the adjacent flight of the chain rail for a substantial distance.
- 15 3. The combination with a chain rail conveyer for flanged wheels, of a track approach having a rail head portion spaced from and in approximately longitudinal alignment with the chain rail and having a portion for supporting a wheel flange when the wheel is passing across the space between the chain rail and said rail head por-

tion, and means for supporting the forward 65 extremity of said flange-supporting portion independently of the chain rail.

4. The combination with a pair of conveyer chains provided with rail head sections, of a track approach having a rail head portion spaced from and in approximately longitudinal alignment with one flight of each of said chains, and a wheel-flange supporting member extending from each rail head portion to a point at the 70 inner side of each chain, the said supporting members serving to support and guide the car wheels passing across the space between chain rail sections and said rail head portions.

5. The combination with a pair of movable tracks for flanged wheels, of rail approaches having rail head portions spaced from said tracks, and rigidly mounted wheel-flange supporting members each disposed adjacent to one side of one of the tracks and serving to bridge the space between adjacent ends of said tracks and rail heads.

6. The combination with a pair of movable tracks for flanged wheels, of rail approaches having rail head portions spaced from said tracks, and wheel-flange supporting members each disposed adjacent to one side of one of the tracks and serving to 90 bridge the space between adjacent ends of said tracks and rail heads, the said rail heads having portions of reduced width extending alongside of the flange-supporting members and disposed alongside of the movable tracks.

7. Car transfer apparatus comprising a conveyer chain composed of links each provided with a rail head section, a pair of guide wheels around which said chain passes, a link-supporting member between the wheels, and a track approach from which cars may be directed to said chains, the said approach extending forwardly of the adjacent end of said supporting member a distance not materially less than the length of a link.

8. Car transfer apparatus comprising a conveyer chain composed of links each provided with a rail head section, a pair of guide wheels around which said chain passes, a link-supporting member between the wheels, a track approach from which cars may be directed to said chains, the said approach extending forwardly of the adjacent end of said supporting member a distance not materially less than the length of a link, and means for supporting the forward end of said approach independently of said chains.

9. The combination with a pair of longitudinally movable tracks for car wheels and the like, of a pair of rail approaches, each

having a rail head portion whose forward end is of reduced width and is disposed alongside of one of said movable tracks.

10. The combination with a chain rail conveyor, of a fixed track rail disposed in substantially longitudinal alinement with one flight of said chain rail, and a narrowed wheel-supporting extension associated with

said fixed rail and extending for a substantial distance alongside of said chain flight, ¹⁰ said extension serving to support a vehicle during transfer from the fixed rail to the chain rail.

In testimony whereof I the said Louis E. ENDSLEY have hereunto set my hand.

LOUIS E. ENDSLEY.
